UNITED STATES PATENT OFFICE.

HERBERT J. FRINK, OF HOLYOKE, MASSACHUSETTS.

ADJUSTABLE BEARING-BOX.

1,132,572.

Specification of Letters Patent. Patented Mar. 23, 1915.

Application filed July 16, 1914. Serial No. 851,285.

To all whom it may concern:

Be it known that I, HERBERT J. FRINK, a citizen of the United States, residing in the city of Holyoke, county of Hampden, and 5 State of Massachusetts, have invented certain new and useful Improvements in Adjustable Bearing-Boxes, of which the following is a specification.

This invention relates to bearings or journal boxes and more particularly to boxes for supporting the calender rolls in a paper calendering machine.

An object of the invention is to provide a journal box construction, especially adapted 15 for use in paper calendering machines, embodying in combination an eccentric sleeve or bushing in which the journal of the roll is adapted to rotate and a journal box arranged to support the sleeve having a cored 20 chamber through which water or other cooling medium is adapted to circulate, whereby the bushing and thus the bearing surfaces may be kept from overheating. In this construction a removable cap is provided on the 25 end of the journal box by means of which access may be had to the bushing for adjustment without disturbing the journal box and its cored chamber.

A further object is to provide a paper 30 calendering machine having its rolls mounted in journal boxes one set on each side of the machine, constructed as stated, which boxes in each vertical set are adjustable in vertical ways of the frame. The latter ad- 35 justment is arranged to coöperate with the bushing adjustment to line the axes of the rolls accurately in the two dimensions as desired. The cored chambers of the journal boxes arranged in the vertical ways on each 40 side of the machine are connected by flexible hose so that water can circulate from one journal box to another.

Another object of the invention is to provide a journal box of the class described 45 which is adapted to support the shaft or journal of a calender roll in an adjustable manner.

Another object is to provide a journal box 50 wherein the shaft is shiftable horizontally for the purpose of alining the axis thereof with the axes of adjacent shafts.

Another object is to provide in connection 55 with an adjustable bearing of the class described special lubricating devices to co-operate therewith.

A further object is to provide in a journal

box for a calender roll an adjustable device to receive the end thrust of the roll.

Other objects will appear in the detailed description to follow.

My improved journal box is particularly applicable to the paper calendering machine. Such a machine, in general, comprises a series of rolls mounted vertically one above the other, with the peripheral surface of each roll pressing in contact against an adjacent roll. The journal boxes for each roll are slidably mounted in ways permitting vertical movement for the adjustment of the axes of the rolls in various horizontal 60 planes. The ordinary calender provides no means for shifting the roll horizontally for the purpose of alining the axis of the roll in a vertical plane with the axes of adjacent rolls. It is common knowledge in the paper 65 calendering art that, unless the axes of the calender rolls are properly alined so that they all lie in the same vertical plane, the paper passing through the machine between these rolls will be wrinkled or torn. A ma- 70 chine originally built with the rolls in proper adjustment may after being used some time get out of adjustment. I seek to provide by my invention, suitable means for 75 adjusting in a most convenient manner, the 80 journal of the roll in a horizontal direction, whereby I may so adjust each roll that the axes of all the rolls will lie in one vertical plane.

In the accompanying drawings wherein I 90 have shown a preferred embodiment of my invention—Figure 1 is a plan view of my improved journal box; Fig. 2 is an elevational view partly in section, taken on the line 2—2 of Fig. 1 and looking in the direction of the arrows; Fig. 3 is a longitudinal 95 sectional elevation taken on the median line of Fig. 1; Fig. 4 is a perspective view of the eccentric bushing; and Fig. 5 is a diagrammatic view illustrative of the purpose and 100 application of my invention. Fig. 6 is a dia- 105 grammatic view showing the manner of mounting the journal boxes in vertical sets and the way in which the cored chambers of the boxes are connected by flexible hose to provide a path for water around the several bearings in the stack.

Referring to the drawings, 1 represents the body portion of the journal box which is formed on either side thereof with integral outwardly extending flanges 2 and 3. Each flange 2 is provided with finished sur-

faces 2' and 2² at right angles to one another, which abut the ways of the calender indicated by dotted lines at 31 in Fig. 1. Each flange 3 is provided with a finished 5 surface 3' for the same purpose as the surface 2'. Removable flanges 4, secured to flanges 3 by bolts 5, abut the ways of the calender on the surface 4' and restrain the box in place therein.

- 10 Within the body portion 1 is mounted a bushing 8 bored eccentrically to receive the journal 7 of the calender roll 6. An enlarged portion 8' of the bushing 8 extends beyond the body 1 as clearly shown in Fig. 15. In this portion 8' are provided at suitable intervals holes 11, which are adapted to receive a spanner wrench, whereby the bushing 8 may be turned. The bushing 8 is also formed with a circumferential groove 13 20 which is adapted to receive the ends of a pair of set screws 12. The latter are suitably mounted in the body 1 as shown in Figs. 1 and 2 and serve to clamp the bushing 8 in position. The bushing 8 is furthering 25 more provided with two series of slotted holes 9 adapted to allow oil from holes 10 in the body to pass to the journal 7. These holes 9 are so arranged that one of each series is always in communication with a hole 30 10, no matter what angular position the bushing 8 may assume.

The outer end of the journal box is closed by a cap 20 removably secured to the body 1 by cap screws 21. Mounted in a circular recess 26 in the end wall of the cap 20 and axially movable therein by the adjusting screw 22 is a plate 23. The latter is held against rotation by a pin 24 which is fixed in the cap 20 and loosely engages with a 40 hole in the plate 23. The plate 23 bears against the end face 25 of the journal 7 and forms an adjustable means for receiving the end thrust of the journal 7. The plate is provided with a vertical oil groove 27 extending from the upper edge to the center of the plate. The groove 27 is located in under the oil hole 19 in the cap 20 and is adapted to convey oil therefrom to the end face 25 of the journal 7.

- 50 The rear portion of the body is formed with an inturned flange 28 which forms a circumferential channel 29. The latter is adapted to receive the oil which emerges from oil grooves 32. The oil leaves the body 55 1 by means of passage 18, communicating with a pocket 30 in the channel 29 at the bottom of the journal box, as clearly shown in Fig. 3. The oil flowing from opening 17 of passage 18 is directed by any suitable 60 means to the oil holes 10 of the journal box immediately below, as by means of a short pipe or hose, not shown, it being understood that the journal boxes are arranged as shown in Fig. 6.

65 If it is kept in mind that the journal

boxes in each set are adjustable vertically and their bushings for the journals of the rolls can adjust the latter horizontally it will be seen that the desired results are obtained if the journals can be properly oiled 70 and kept from overheating. The oiling system especially adapted for the purpose has been described. The overheating is prevented by providing in each journal box a cored space 16 nearly surrounding the periphery of the bushing. Water can flow from one opening, as 14, (see Figs. 1 and 2) to this space 16 and from the other opening 15, thus circulating around the bushing to keep the latter cool. Referring to Fig. 6, 80 the exit opening 15 of one journal box is preferably connected to the inlet opening 14 of the journal box just below throughout the set, by flexible hose 50 and a pump is used to force the water from the last exit 85 opening 15 to the inlet opening of the top journal. Thus a constant flow of water is kept in circulation to insure the cooling of all the bearing surfaces in the journals.

The general operation of my device will 90 be clearly understood with reference to Fig. 5. This figure shows diagrammatically two rolls *a* and *b*, whose axes *c* and *d*, respectively, are out of alignment. Since these axes *c* and *d* do not lie in the same vertical 95 plane, paper passing through the rolls *a* and *b* will be torn or wrinkled. By my adjustable journal box, hereinbefore disclosed, I may conveniently align either roll *a* or *b* with the other so that their axes *c* and *d*, respectively lie in a common vertical plane. To do this it is simply necessary to remove the end cap 20 of the journal box, insert a spanner wrench into a hole 11, and turn the bushing 8. This operation will, by reason 100 of the eccentric bore of the bushing throw the shaft in a horizontal direction whereby proper alignment may be secured. It is to be noted particularly that although operation of shifting the eccentric throws the shaft horizontally, it is also moved vertically to some degree. Since, however, the body 1 is freely slideable in the ways 31 of the calender, the rolls drop into contact and nullify this vertical movement. Whatever 105 the adjustment of any of the journals, the cooling system is not interfered with, but remains in constant use. Thus, I have provided efficient means for alining the rolls of a paper calendering machine at any desired 110 time so that the axes of the rolls will all lie in a common vertical plane and the journal will not overheat.

115 It is recognized that many modifications may be made in the structure of my invention which is more truly defined in the appended claims than in the foregoing specific description.

120 What I claim is:

125 1. The combination with a paper calen-

dering machine involving a suitable frame formed with vertically disposed ways thereon and a series of calendar rolls, of journal boxes slidably mounted on said ways, bushings within said boxes, said bushings being formed with eccentrically disposed holes adapted to support said rolls, means to turn said bushings in said boxes whereby said rolls are shiftable in a horizontal direction, 10 and means to lock said bushing against rotation.

2. A journal box for a paper calendering machine, comprising, in combination, a suitable body portion formed with integral 15 flanges thereon, other flanges removably secured to said body, a bushing within said body formed with an eccentrically disposed hole adapted to receive the shaft of a calender roll, means to rotate said bushing within 20 said body, and means to lock said bushing against rotation.

3. A journal box for a paper calendering machine, comprising, in combination, with a suitably formed body, a bushing therein 25 formed with an eccentrically disposed hole adapted to receive the shaft of a calender roll, said bushing provided with an enlarged portion extending beyond said body, means in said enlarged portion to rotate said bush- 30 ing relative to said body, said bushing being formed with a circumferential groove, set screws in said body adapted to engage in said groove and clamp said bushing to said body and a cap removably secured to said 35 body and adapted to cover said enlarged portion of said bushing.

4. A journal box for a calendering machine, comprising, a suitably formed body portion, a bushing rotatably mounted there- 40 in, said bushing being provided with an eccentrically disposed hole adapted to receive the shaft of a calender roll, a flanged portion on said bushing extending outwardly from said body, means in said flanged portion to 45 turn said bushing, means in said body to lock said bushing against rotation, a cap removably secured to said body and adapted to inclose said flanged portion, a plate in

said cap adapted to bear against the end face of said roll, and means to move said plate 50 axially with respect to said roll.

5. A journal box for a calendering machine, comprising in combination, a body, an oil hole in said body, a bushing formed with an eccentrically disposed hole adapted to 55 receive the shaft of a calender roll, a series of slotted holes in the periphery of said bushing arranged in line with said hole in said body and adapted to convey oil to said shaft, means to turn said bushing in said 60 body, said slotted holes being arranged so that one at least is always in communication with said hole in said body, and means to lock said bushing against rotation.

6. A paper calendering machine provided 65 with a journal box mounted in vertical ways of the machine for adjustment, an eccentric bushing carried by the journal box, adapted to receive the journal of a calender roll, means to turn the bushing in the journal box 70 to adjust the axis of the roll horizontally, said journal box having a chamber surrounding the greater part of the bushing with an inlet and outlet at opposite ends whereby water may be circulated there- 75 through for cooling the bearing surfaces.

7. A paper calendering machine provided with vertical ways on each side thereof, two series of journal boxes, one mounted in ways at each side of the machine and individually 80 adjustable therein, horizontally adjustable bearing means carried by each journal box to receive and adjust a calender roll bearing, each journal box having a chamber embrac- 85 ing, but separated from the bearing surfaces by a heat conducting medium, and a flexible pipe connection between the chamber of one journal box to the chamber of the next one in each series, whereby the calender rolls may be adjusted vertically and horizontally 90 and the bearing surfaces kept from overheating at all times.
